UNITED STATES PATENT OFFICE.

CHARLES F. L. KAUFMANN, OF SANTA ANA, CALIFORNIA.

BOAT SEARCH-LIGHT.

1,292,475.

Specification of Letters Patent. Patented Jan. 28, 1919.

Application filed July 1, 1918. Serial No. 242,832.

To all whom it may concern:

Be it known that I, CHARLES F. L. KAUFMANN, a citizen of the United States, and resident of Santa Ana, in the county of Orange and State of California, have invented new and useful Improvements in Boat Search-Lights, of which the following is a specification.

The present invention relates to search-lights, and more particularly those mounted for turning movement to direct the beam of light in various directions at will.

It is the object of the invention to provide a searchlight mounted for turning movement and having novel means of manual control, in order that the light can be readily moved in various directions by the simple manipulation of a handle.

Another object is the provision of such a device which enables the searchlight or lamp located above the roof or deck of a boat or vehicle to be readily controlled from below, in order that the light can be directed in different directions even though the lamp is on the exterior and the operator positioned within the cabin or the like.

A further object is to provide controlling means for the searchlight so arranged that the turning movement of a handle will turn the lamp in a horizontal or other plane with a sweeping action, and through a complete circle if desired, while the handle can also be shifted to turn or tilt the lamp in a vertical or other plane, to change the plane in which the lamp turns with the handle when turned. Thus, for example, the lamp can be turned about a vertical or nearly vertical axis by turning the handle, to direct the light in various directions about said axis, and by raising and lowering the handle, the light can be raised and lowered to direct it on distant or near objects.

A still further object is the provision of a searchlight having controlling means of the nature indicated, and which can be conveniently used as a hand lamp, trouble or inspection light about the boat or vehicle.

The invention also aims to provide a searchlight and control of the character specified which will be simple and inexpen-

sive in construction, and thoroughly practical and efficient in use.

With the foregoing and other objects in view, which will be apparent as the invention is better understood, the invention resides in the construction and arrangement of parts as hereinafter described and claimed, it being understood that changes can be made within the scope of what is claimed without departing from the spirit of the invention.

The invention is illustrated in the accompanying drawings, wherein—

Figure 1 is a side elevation of the searchlight and control, a portion being broken away.

Fig. 2 is a side elevation showing the searchlight as used as a hand lamp for locating trouble or making inspection.

Fig. 3 is a perspective view of the stand with the lamp removed.

Fig. 4 is a side elevation of the handle.

The mounting for the searchlight embodies a suitable stand or support 1 having a base 2 to be fastened in any preferred manner on the roof 3 of a boat cabin or to any other supporting member. The lamp 4 (an electric lamp being preferably used) is mounted on the stand 1 for turning movement in two different planes at right angles with one another, and although the lamp is shown as being capable of horizontal and vertical turning movements, it can be readily arranged to turn in other planes as circumstances may dictate. In order to so mount the lamp 4, the upper end of the stand 1 has a fork 5, and a lamp supporting arm 6 has a bearing 7 at one end pivoted within the fork 5 on a horizontal pivot 8 to swing upwardly and downwardly in a vertical plane, said arm being provided at its free end with a vertical bearing 9 which is preferably split and provided with a clamping screw 10. This arm 6 is normally substantially horizontal so that it can be raised and lowered, and the lamp 4 has a rearwardly projecting stem 11 provided with a depending shank 12 journaled for rotation through the bearing 9. The shank 12 has a shoulder 13 seatable above the bearing 9 to support said

shank, and said shank being loose within the bearing 9 permits the lamp 4 to turn about the vertical or substantially vertical axis of the shank 12 in a horizontal plane, so as to direct the light in various directions around the stand 1, and when the arm 6 is swung upwardly and downwardly on the pivot 8 the lamp is tilted vertically, for either raising or lowering the beam of light as desired and to determine the plane in which the lamp 4 will turn with the shank 12. The electrical cord 14 containing the conductors for the lamp 4 dangles from the end of the stem 11, so as not to impede the movement of the lamp. By tightening the screw 10, the shank 12 will be clamped in the bearing 9, to prevent turning movement thereof, and the pivot 8 can also be a screw to clamp the bearing 7 in the fork 5 when turning movements of the shank 12 and arm 6 are not wanted. A cotter pin 15 or other retaining element is inserted through the shank 12 underneath the bearing 9 to hold said shank in place.

25. The control is very simple yet very effective, and includes a rod 16, disposed vertically as shown, in substantial alinement with the shank 12 below the same and sliding loosely through an aperture or opening 17 in the base 2 of the stand 1. The rod 16 also extends through an opening provided in the roof or support 3 and is provided at its lower end or that end remote from the lamp with a suitable handle 18 for turning and sliding said rod, which has its upper end connected by a universal joint with the lower end of the shank 12. This joint includes a coupling 19 pivoted, as at 20, to the upper end of the rod 16, and by means of a cotter pin or removable pivot 21 to the shank 12 at right angles with the pivot 20. Such joint enables the shank 12 and rod 16 to assume different angles relatively to one another and still rotate as a unit.

45. In operation, it will be noted that the handle 18 by being grasped by the hand and turned with the rod 16 will turn the shank 12 and lamp 4 carried thereby, so as to turn the light to different directions around the stand 1, and through a complete circle. By pushing upwardly or pulling downwardly on the handle, so as to shift or slide the rod 16 longitudinally, this will either raise or lower the shank 12 and arm 6. In this way, the lamp can be tilted or turned upwardly and downwardly, and the universal joint or flexible connection between the shank 12 of the lamp mounting and operating rod 16 enables said rod to readily turn the shank 12 at various angles thereof. The two motions of the handle 18 can be accomplished either individually or jointly, whereby the operator has full control of the position of the lamp. The handle member serves as an ex-

65. tension for the lamp shank to permit con-

trol thereof easily and in a simple manner and the handle member forms a unit with the shank to move as a part or extension thereof instead of through the medium of levers, links and the like.

To use the lamp as a hand lamp, trouble light or inspection light, it is only necessary to remove the cotter pins 15 and 21, which permits the shank 12 to be lifted from the bearing 9 with the lamp 4, as seen in Fig. 2.

Having thus described the invention, what is claimed is:

1. A lamp, a swinging mounting therefor, the lamp being carried by the mounting for tilting movement therewith and being supported by said mounting for rotation relatively thereto, and a single operating handle connected to said lamp as an extension thereof to move as a unit therewith, so as to turn with the lamp relatively to the mounting and to push and pull the lamp for swinging the mounting.

2. A lamp, a support, a swinging member carried by the support, a shank supporting the lamp and mounted to turn in said member, and a single operating handle connected to said shank as an extension thereof to move as a unit therewith.

3. A lamp, a swinging arm, said lamp having a shank journaled through the arm at an angle thereto, and a single operating handle connected to said shank as an extension thereof to move as a unit therewith.

4. A lamp, a swinging mounting therefor, the lamp being carried by the mounting for tilting movement therewith and being supported by said mounting for rotation relatively thereto, and an operating rod slideable longitudinally and rotatable about its axis having a universal joint connection with the lamp to move as a unit therewith.

5. A lamp, a fixed support, a member carried by the support for swinging movement, the lamp being carried by said member to swing therewith for tilting movement and supporting the lamp for rotation relatively to said member and support, and an operating rod slideable longitudinally in the support and rotatable about its axis having a universal joint connection with the lamp to move as a unit therewith.

6. A lamp, a support, a swinging member carried by the support, a shank supporting the lamp and mounted to turn in the said member, and a rotatable and slideable operating rod having a universal joint connection with said shank and forming an extension thereof movable as a unit therewith.

7. A lamp, a stand, an arm pivoted to the stand and projecting to one side thereof, a shank supporting said lamp and journaled through said arm, and a rotatable and slideable operating rod having a universal joint connection with said shank and operating through the base of the stand, the rod form-

ing an extension of the shank and being movable as a unit therewith.

8. A lamp having a shank, a bearing in which said shank is removably journaled, 5 and operating means connected to the shank and detachable therefrom for the withdrawal of the shank from the bearing.

9. A lamp having a shank, a bearing mounted for swinging movement and in

which said shank is removably journaled, 10 and rotatable and slidale operating means having a flexible connection with said shank and detachable therefrom for the withdrawal of the shank from the bearing.

In testimony whereof, I hereunto set my 15 hand this 11th day of June 1918.

CHARLES F. L. KAUFMANN.
